POWER OPERATED SLIP

Walter E. Liljestrand, Houston, Tex., assignor to
 Mission Manufacturing Company, Houston,
 Tex., a corporation of Texas

Application October 21, 1946, Serial No. 704,672

11 Claims. (Cl. 24—263)

1

The invention relates to a mechanism for operating the slips used in suspending pipe during the rotary method of drilling wells.

With the advent of deeper and deeper drilling, the size, length, and weight of the pipe which must be suspended has increased substantially so that there is a definite problem in properly suspending or supporting the pipe to insure that it will be firmly held and to then effect release of the slips and supporting structure in such a manner as to avoid damage and injury to the pipe to eliminate the drudgery of handling the heavy slips, and in fact, to improve the method and apparatus for handling the slips and supporting the pipe.

It is one of the objects of the present invention to provide a power operated mechanism for manipulating the slips so that they will be automatically retracted to permit a full opening when the slips are raised to inactive position.

Another object of the invention is to provide a slip handling mechanism wherein by a straight lift operation the slips are not only withdrawn from the slip bowl but are also retracted from interference with operations being conducted through the rotary table and slip bowl.

Another object of the invention is to provide a slip operating mechanism which will automatically lift and retract the slips or lower and insert the slips when the device is power operated.

Another object of the invention is to provide the power operating mechanism for slips which can be moved away from the rotary table to an inactive position which will not interfere with the use of the rotary table when the slips are not being used.

Still another object of the invention is to provide a lift mechanism for slips which embodies a lift ring having a trackway therein to support and retract the slips automatically upon vertical movement thereof.

Still another object of the invention is to provide a slip operating mechanism wherein the slips are provided with a slip post or handles which are received in a lift ring so as to elevate and retract the slips or to lower and insert the slips relative to the slip bowl.

Still another object of the invention is to provide a pneumatic power operated mechanism for raising and lowering a slip operating ring.

Still another object of the invention is to provide a lift ring for slip operating mechanism having a trackway therein which will take advantage of the components of force encountered so

2

as to lift and retract the slips in a single operation or to lower and insert the slips in a single operation.

It is also an object of the invention to provide a slip operating lift ring which can be moved laterally away from the position over the slip bowl.

A still further object of the invention is to provide a control assembly for slip operating mechanism.

It is also an object of the invention to provide a slip operating lift ring having a trackway of a peculiar configuration such that when a slip is supported therein, there will be a tendency to retract the slip as soon as it is lifted out of the slip bowl.

Still another object of the invention is to provide an adapter ring for rotary tables so as to guide a set of power operated slips into the slip bowl upon locking movement thereof.

A still further object of the invention is to provide a power operated slip handling mechanism which will permit the making up and the breaking out of pipe joints while the slips are supporting the pipe and connected to the mechanism.

It is an object of the invention to balance the supporting structure for slips in a power operated mechanism so that the slips may be lifted to a position to be moved laterally from the slip bowl and returned thereto and inserted in the slip bowl without additional guidance.

Other and further objects of the invention will be readily apparent when the following description is considered in connection with the accompanying drawings, wherein:

Fig. 1 is a top plan view looking down on the power operating mechanism and illustrating the mechanism as moved to retracted position as shown by the dotted lines.

Fig. 2 is a side elevation of the mechanism in use and showing the slips in pipe supporting position in the rotary table.

Fig. 3 is a top plan view looking down on the operating mechanism with certain parts broken away to illustrate the construction and showing the retracted position of the slips in dotted line.

Fig. 4 is a vertical sectional view showing the slips in pipe supporting position and the lift ring lowered so as to have inserted the slips and with the slips and the lift ring shown elevated in dotted lines.

Fig. 5 shows a modified form of the configuration of the trackway by which the retracting movement of the slips is performed.

Fig. 6 shows another modification of the configuration of the trackway.

Fig. 7 shows a diagrammatic arrangement of the power control mechanism with some of the valve assemblies illustrated in section.

Referring to Fig. 2, a rotary table has been illustrated which is supported by the derrick over the location where the well bore is being drilled. This rotary table embodies the stationary base 2 and the rotating top 3 which top is best seen in section in Fig. 4. This top has a non-circular opening 5 therein which is arranged to receive the drive bushings for gripping the drill stem or other pipe 6 which is to be rotated in the well bore.

It is believed to be well understood that in the rotary method of drilling wells, a section of pipe is connected to the drill bit and this pipe is either gripped by the rotary table or by other suitable section of pipe so that rotation is imparted thereto. As the drill bit penetrates the earth formation, additional sections of pipe are added. When the drill bit is to be renewed or for some other reason removed from the well bore, the string of pipe thus assembled must be raised, then supported and a number of sections of the pipe removed. This operation is repeated until all of the pipe has been withdrawn from the well. The bit is changed or such other operation carried on as desired and when drilling is to be resumed, the pipe is reinserted usually by adding two, three or four sections of pipe at a time. In thus manipulating the pipe and in fact handling other pipe in the well bore, that part remaining in the well must be suspended while the sections are being removed or added thereto. The rotary table is provided with a tapered area 8 which is generally known as the slip bowl and is arranged to receive a set of slips 10, usually made up of a plurality of segments 11, three of which are seen in Fig. 3. These segments are usually tapered and have a support face 12 arranged to fit the tapered slip bowl 8 and also provided with the jaw sections 13 arranged to engage the periphery 14 of the pipe 6, so as to firmly grip the pipe and, due to the tapered surface 8, move downwardly in the rotary table so as to firmly and securely support the pipe.

When the pipe is to be again moved after having once been gripped with the slips, the pipe must be elevated slightly, then the slips withdrawn. As the wells are drilled deeper and deeper, it is not uncommon to support 200,000 or 300,000 pounds of pipe upon the set of slips. The slips in turn must move substantial weight in order to support such tremendous loads and large slips are heavy and difficult to handle manually.

The present invention therefore contemplates a slip operating mechanism which is best seen in side elevation in Fig. 2. The essential part of this mechanism is the slip lift ring 15 which is best seen in section in Fig. 4. This ring includes an outer rim 16, a base 17, and the top plate 18. It has an annular opening 19 through the top plate, and the base plate as seen in Fig. 4 is inclined upwardly and inwardly to provide a surface 20 which in turn is joined by a somewhat steeper inclined surface 21. An upstanding flange 22 forms the inner periphery of the base ring. These plates 20 and 21 are substantial and rigid so as to support the weight of the set of slips.

An apron 24 is arranged inside of the lift ring 15 so as to define a space or chamber 25 therein which is generally annular in form.

This lift ring 15 is provided with a gate 30 hinged at 31 and latched in position in the ring by the latch 32. This gate permits movement of the ring laterally about the pipe such as 6 where the pipe is already in the hole and the lift device is to be used.

Fig. 3 shows the lift ring positioned about the pipe with the gate closed because the latch arm 36 thereof engages over a pin or stop 37 in the lift ring 15. The gate is shown open in the dotted line position and a spring mechanism 39 may be used to hold it in either open or closed position as shown.

The lift ring 15 may be raised and lowered but the arm 40 to which the lift ring is pivoted by the plates 41 and pivot pin 42 as best seen in Figs. 1 and 2.

This arm 40 is in turn pivoted by the pin 43 upon a yoke 44 affixed to the housing 45 which is arranged to telescope over the cylinder 46. Arranged inside of the housing 45 is a plunger 47 as best seen in Fig. 7. The chamber 48 within the cylinder 46 is arranged to receive a fluid under pressure from the pipe 49 which is controlled by a valve 50. In this way pressure fluid may be introduced to or released from the chamber 48 so as to elevate the housing 45, the arm 50 and the lift ring 15 or to lower it as desired.

Arranged on the housing 45 is an arm 52 which carries a stem 53 extending into a cylinder 54. This cylinder 54 is arranged to receive or discharge fluid under pressure through the piping connection 55 which is also connected to the valve 50. The application of pressure in this cylinder 54 applies a positive movement to move the operating mechanism and the slips downwardly into pipe receiving position. In other words, the slips may be operated by power to be lifted upwardly and may also be power actuated in moving downwardly.

The particular details of the slip manipulating mechanism include a particular form of slip segment 11 where there is an upstanding portion or post 60. Affixed in this post is an outwardly and downwardly extending handle 61 having an anti-friction member 62 such as a collar or other device to reduce the friction of the handle upon the portions 20 and 21 of the base plate 17. These portions 20 and 21 serve as a trackway for the handle and as seen in Fig. 4 the lift ring 15 has been lowered so as to allow the slips to move from the dotted line position of Fig. 4 to the full line position. This movement has been accomplished first by virtue of the beveled face 65 on the lower end of the slip segments, which face 65 is arranged to abut a beveled adapter ring 66 carried by the top of the rotary table 3. It will be particularly noted that the dotted line position of the slips in Fig. 4 illustrate the pipe engaging face 13 thereof as being retracted radially outward beyond the narrowest portion of the passage 67 through the rotary table. In this manner a full hole opening is provided for manipulation of the tools and pipe. The manipulating construction for the slips is so arranged that when the slip ring moves downwardly, the toe 65 of the slip will move off of the adapter ring 66 and slide downwardly into the drive bushing opening 5 and the slip bowl 8.

In other words, the force of gravity pulling the slip down will cause it to slide inwardly into pipe supporting position.

When the slips are to be lifted, the power mechanism is operated to raise the slip ring 15.

The vertical upward movement of this slip ring

forces the portion 21 of the trackway against the anti-friction portion of the handles 61 and begins the lifting movement of the slips. Due to the inclined configuration of the portion 21, the lifting force is divided into vertical and horizontal components, the horizontal component tending to urge the handle 61 and the slip segments 11 radially outward. As the slip segments move out of the tapered portion 8, they will be retracted to move upwardly along the surface of the drive bushing 5 and when the beveled toe portion 65 reaches the top of the slip, further outward movement is permitted. By this time, the outer or anti-friction portion of the handle 21 has moved off the steep portion of the trackway 21 and onto the surface 20 as best seen in the dotted line portion of Fig. 4. This position still continues to urge the slips outwardly and in the full elevated position, the slips will move radially outwardly until they abut the stop ring 22 which forms the periphery of the trackway. The dotted line position in Fig. 4 shows the slip post 60 abutting this ring.

It seems obvious that when the lift ring is again lowered, that the slips will negotiate an inward and downward movement because part of the weight of the slips may be supported in the various portions of the rotary table to relieve some of the weight on the handles and anti-friction means, thus allowing the handle to travel upwardly on the trackway until such time as the slips are fully supported in the slip bowl and the lift ring moved downward to its lowermost position as seen in Fig. 4.

On this downward movement the apron 24 comes into service and may engage the anti-friction portion 62 of the handles, urging the handles and the slips inwardly due to the inclined surface of such apron engaging the upper part of the slip handle.

Fig. 5 shows a modified form of the base 17, wherein a straight frusto-conical surface 70 has been provided so that there is a uniform movement as distinguished from the movement obtained with the configuration of the trackway shown in Fig. 1. The remaining structure is identical with that previously described. This form may be used but in actual operation, a greater tendency to move the slips outwardly is desired in the initial movement, whereas, tendency need not be so great toward the upper end of the lifting movement and thus the two inclinations of the trackway have been provided in Fig. 4. Fig. 5 having the straight trackway may be satisfactory in some operations.

Fig. 6 shows a modification or comprise between the forms of Fig. 4 and Fig. 5 in that the surface 72 is an outwardly and downwardly flared or dished surface which gives a greater opening force which is tapered off as the slips reach their maximum elevation.

The plan view of Fig. 3 illustrates details of the slip assembly and the supporting handles whereby a satisfactory operation is obtained. It will be noted that the slip segments are three in number and the two lateral segments are hinged by the pins 74 and 75 to the main slip segment 76. Any desired number of segments may be used but they are preferably hinged together so as to insure satisfactory operation.

As these slip segments are raised and moved backwardly and away from the pipe, the segments 77 and 78 will swing outwardly and rearwardly on an arc around the pins 74 and 75 respectively. This action is obtained due to the

fact that the handles 19 on the segment 77 and 80 on the segment 78 are angularly disposed with respect to the slip segments so that the handles tend to run backwardly and downwardly on the trackway so as to move the slips backwardly away from the pipe to the dotted line position of Fig. 4. This movement not only withdraws the slips from engagement with the pipe but also opens up the slip segments to such a position that the entire slip rings may be swung laterally to the dotted line position of Fig. 1 with the pipe passing between the segments 77 and 78 of the slip. It seems obvious that the slips may be stopped in their rotation in the position of Fig. 3 or if they are in some other position, the operator may manually roll the slips around on the trackway so as to arrange them in full open position.

If the slips have been raised, the arms 79 and 80 will have rolled to the dotted line position of Fig. 3 during the simultaneous retraction of the main slip 76 and all of the parts will then be in the dotted line position of Fig. 3.

The main slip 76 is supported by two arms 81 and 82 which are angularly disposed with respect to each other and the main slip and are arranged to balance the slip with a direct radial outward and inward movement without any circular traveling. These arms are shown in the retracted or dotted line position of Fig. 3. Upon lowering of the lift ring, the slips will travel inwardly but the pivots 74 and 75 will cause them to move circularly as well and they will then return to the full line position of Fig. 1.

Particular attention is directed to the arrangement of the anti-friction roller bearings or such other device as may be provided so as to obtain suitable rolling action upon the trackway. It is not uncommon for the driller to use the rotary table for turning the pipe in uncoupling the pipe sections by holding the section above the rotary table with suitable mechanism gripping the pipe with the slips as seen in Fig. 4 and then rotating the table. Inasmuch as the lift ring 15 is held stationary by the arm 40, it is desirable to permit the slips under these circumstances to turn with the rotary table, and anti-friction rollers as shown in the drawing are therefore arranged on the axis of the arms so as to travel circumferentially around the track. If a single ball bearing is used, such a bearing is capable of rolling in any direction.

If all of the parts are in the contemplated position during such rotation of the rotary table, the anti-friction members on the handles should theoretically at least be positioned midway between the trackway and the apron. If the parts are worn or the pipe is of slightly different diameter than contemplated, then the rollers may engage either the trackway or the apron as the case may be.

In order to hold the ring 15 in extended position relatively to the arm 40, a latch pin 85 is shown in Figs. 1, 2, and 4. This pin may be dropped through openings in the plate 71, the ring 15 and the end of the arm 40 as best seen in the enlarged view of Fig. 4.

The operating mechanism described but briefly heretofore is seen in Fig. 2 and includes in addition to the structure previously described, the upright guide members 90 which as seen in Fig. 1 are in the form of channels to receive the guide rollers 91 carried by the extension arm 92 on the lower end of the housing and upper yoke 75 44.

A bumper or adjustable stop device 93 has been provided and is best seen in Fig. 7. The spring thereon will be of sufficient strength to support the entire lift ring and moving parts of the power assembly so that it acts as a stop but in event some object should strike the lift ring or other parts, the shock thereof would be cushioned by this device. Both the spring thereof and the position of the stop 93 may be adjusted vertically.

When the lift ring is to be moved laterally away from the rotary table, the latch pin 95 seen in Figs. 1 and 2 may be removed so that the arm 40 may pivot about the support pin 43.

The valve 50 is generally known as a four-way valve so that it may be positioned as seen in Fig. 7 to admit pressure fluid through the pipe 49 to elevate the slips while in turn permitting the exhaust of pressure from the cylinder 54 to exhaust through the pipe 55 and the outlet 97. When the lift ring is to be lowered, the valve will be turned so as to permit the pressure to be relieved in the line 48 through the outlet 97 while the inlet pressure fluid is directed through the valve to the pipe 55 to effect a positive downward movement of the slip ring through the plunger cylinders 53 and 54.

A detailed control valve mechanism is shown in section in Fig. 7 as having been incorporated in the base of the cylinder 46.

The pressure fluid entering the chamber 46 through the pipe 49 will be prevented from return through the same path by a check valve 100.

The entering fluid moves upwardly through the passage 101, lifting the valve 102 and permitting the pressure fluid to pass through the opening 103 in a cage 102. This pressure then exerts itself against the plunger 47 and results in elevation of the housing 45 to which the plunger 47 is connected at its upper end.

In order to accurately control the movement of the plunger 47, and consequently the movement of the lift ring 15, a series of valves have been provided in the base portion of the plunger 46 as seen in Fig. 7. One of these is a direct safety valve 105 which will be set to relieve any pressure in the cylinder extending a predetermined amount, such for instance as that caused by striking of the mechanism by the falling of any object.

If the operator desires to release the pressure in the chamber 48, the release valve 107 may be opened by turning the screw 108.

Neither of these valves 106 or 107 will be normally used because the escape of the pressure fluid will be governed by a control valve 110. This control valve has a small seating surface 111 which remains closed during the introduction of pressure fluid to lift the ring. It also has a larger surface or shoulder 112 which may be exposed to pressure introduced through the branch line 113 which leads off from the pressure line 55 leading to the cylinder 54 for forcing the mechanism downwardly. Thus when the valve 50 is manipulated to cause the lowering of the lift ring, the pressure applied in the pipe 55 and the cylinder 54 against the piston or plunger 53 will also pass in the branch pipe 113 and effect opening of the valve 110 against the spring 115 whose compression may be adjusted.

The opening of the control valve 110 allows escape of pressure from the chamber 48 past the valve 102, which is normally held open by its supporting spring, and into the outlet passage 118. The amount of pressure fluid permitted to escape from this outlet passage 118 is

controlled by a choke screw 120 which may be turned to adjust the escape opening 121 and allow the lowering movement of the piston 47. It is desired of course to prevent shock of the dropping of the slip ring and the slip and with this in mind, an air chamber 121 has been provided in the base of the plunger 47. A weight disk 122 is freely slideable in this chamber 121 and is arranged to engage the stem 123 extending upwardly from the valve 102. As the plunger 47 moves downwardly below the position shown in Fig. 7, the weight of this disk 122 will overcome the spring supporting the valve 102 and cause the valve to close. The closing of this valve 102 traps the pressure fluid in the chamber 48 and the compression thereof serves to slow down the movement of the plunger 47 and will bring it to a stop at about the time that the arm 42 engages the stop pin 93.

To insure the full lowering movement of the lift ring 15, however, a bleed nipple 125 is shown as positioned in the base of the cylinder in a passage leading to an outlet 118. This bleed opening 125 is normally held closed by a valve 126 urged against the nipple but which will be so set as to permit the gradual escape of more than a predetermined pressure from the chamber 48. A check valve prevents the escape of all of the pressure from the chamber 48 so that the chamber may be readily filled again without having to build up the residual pressure which can be trapped by this check valve 126.

It seems obvious that these various valves may be adjusted and arranged so as to accurately control the movement of the plunger 47 and the lift ring 15. The manipulations previously described will be reversed when the valve 50 is reversed.

A practical advantage of the mechanism just described will be apparent from Fig. 1 due to the provisions of the double pivot pins 42 and 43. The removal of the locking pins 85 and 95 permits a swinging and sliding action of the lift ring and the arm 40 so that the gate 30 may be swung around as the lift ring moves away from the pipe. A driller's position on the rig is usually adjacent the upper right hand corner of Fig. 1 so that the lift ring, when moving away from the pipe, will permit a clear view of the rotary table by the driller and so that the lift ring may be readily swung clear of the rotary table and to a now unused portion of the derrick floor below and to the right of the operating mechanism as shown in dotted lines of Fig. 1.

The parts are so arranged that a single operator may push the lift ring to the inactive position or may return it for use. The ring may be returned from the dotted line position of Fig. 1 by the operator grasping the gate and pulling on the ring. The ring will then first pivot about the pin 42 so that the gate opening will be turned toward the pipe. A pull across the top of the rotary table will then cause the pin 43 to begin to turn so that the ring will finally assume the full line position of Fig. 1. The latch pins 85 and 95 may be now dropped into position. This slip handling mechanism is so simple and readily operable that it has been found that the drillers and operators will use it for supporting and handling a pipe where only a single connection is to be made and of course it is to also be used when doubles, thrubbles or fourables of pipe are being connected.

Broadly the invention contemplates a simple and economical power operated slip mechanism

which will actuate the slips both vertically and laterally from a single support.

What is claimed is:

1. A slip operating mechanism including a lift ring adapted for placement over a rotary drilling table, said ring having an opening and gate for passage of the ring to and from a pipe, a set of slips to fit the rotary table and suspend a pipe therein, said slips being suspended from said ring, an arm pivotally supported radially of the table to support said ring for lateral swinging over said rotary table, rotatable means on said slips which is rotatable in said ring as said slips rotate when gripping the pipe including a handle, a trackway in said ring to guide said rotatable means and thereby said handle as the ring is raised so as to retract the slip segments and provide a full hole opening, and means to raise and lower said arm and lift ring, said rotatable means normally being disposed above said trackway when said slips are gripping the pipe.

2. A slip operating mechanism including a lift ring adapted for placement over a rotary drilling table, said ring having an opening and gate for passage of the ring to and from a pipe, a set of slips to fit the rotary table and suspend a pipe therein, said slips being suspended from said ring, an arm pivotally supported radially of the table to support said ring for lateral swinging over said rotary table, rotatable means on said slips which is rotatable in said ring as said slips rotate when gripping the pipe including a handle, a trackway in said ring to guide said rotatable means and thereby said handle as the ring is raised so as to retract the slip segments and provide a full hole opening, and means to raise and lower said arm and lift ring, said rotatable means normally being disposed above said trackway when said slips are gripping the pipe, said handles having anti-friction means thereon to travel said trackway.

3. A slip operating mechanism including a lift ring adapted for placement over a rotary drilling table, said ring having an opening and gate for passage of the ring to and from a pipe, a set of slips to fit the rotary table and suspend a pipe therein, said slips being suspended from said ring, an arm pivotally supported radially of the table to support said ring for lateral swinging over said rotary table, rotatable means on said slips which is rotatable in said ring as said slips rotate when gripping the pipe including a handle, a trackway in said ring to guide said rotatable means and thereby said handle as the ring is raised so as to retract the slip segments and provide a full hole opening, and means to raise and lower said arm and lift ring, said rotatable means normally being disposed above said trackway when said slips are gripping the pipe, said trackway comprising a plurality of inclined surfaces sloping radially outwardly and downwardly so that such trackway serves to control the movement of the slips.

4. A slip operating mechanism including a lift ring adapted for placement over a rotary drilling table, said ring having an opening and gate for passage of the ring to and from a pipe, a set of slips to fit the rotary table and suspend a pipe therein, said slips being suspended from said ring, an arm pivotally supported radially of the table to support said ring for lateral swinging over said rotary table, rotatable means on said slips which is rotatable in said ring as said slips rotate when gripping the pipe including a handle, a trackway in said ring to

guide said rotatable means and thereby said handle as the ring is raised so as to retract the slip segments and provide a full hole opening, and means to raise and lower said arm and lift ring, said rotatable means normally being disposed above said trackway when said slips are gripping the pipe, said trackway comprising a frusto-conical surface.

5. A slip operating mechanism including a lift ring adapted for placement over a rotary drilling table, said ring having an opening and gate for passage of the ring to and from a pipe, a set of slips to fit the rotary table and suspend a pipe therein, said slips being suspended from said ring, an arm pivotally supported radially of the table to support said ring for lateral swinging over said rotary table, rotatable means on said slips which is rotatable in said ring as said slips rotate when gripping the pipe including a handle, a trackway in said ring to guide said rotatable means and thereby said handle as the ring is raised so as to retract the slip segments and provide a full hole opening, and means to raise and lower said arm and lift ring, said rotatable means normally being disposed above said trackway when said slips are gripping the pipe, said trackway comprising a frusto-conical surface.

6. A slip operating mechanism including a lift ring adapted for placement over a rotary drilling table, said ring having an opening and a gate for passage of the ring to and from a pipe, a set of slips to fit the rotary table and suspend the pipe therein, said slips being suspended from said ring, said slips including a pair of slips having unconnected longitudinal edges, pivot means connecting their other longitudinal edges, handle means on each of said slips extending outwardly and rotatable in said ring, a downwardly and outwardly inclined trackway in said ring engageable by said handle means so that the slips are lifted from within the drilling table and retracted by pivotal movement of the pair of slips about their pivot means to separate said unconnected longitudinal edges to provide a full hole opening when the lift ring is lifted.

7. A slip operating mechanism including a lift ring adapted for placement over a rotary drilling table, said ring having an opening and gate for passage of the ring to and from a pipe, a set of slips to fit the rotary table and suspend the pipe therein, said slips being suspended from said ring, said slips including a pair of slips having unconnected longitudinal edges, pivot means connecting their other longitudinal edges, handle means on each of said slips extending outwardly and rotatable in said ring, a trackway in said ring engageable by said handle means and tapering downwardly and outwardly thereon whereby the slips are lifted and retracted by pivotal movement of the pair of slips about their pivot means to separate said unconnected longitudinal edges as said ring is moved upwardly.

8. A slip operating mechanism including a lift ring adapted for placement over a rotary drilling table, said ring having an opening and gate for passage of the ring to and from a pipe, a set of slips to fit the rotary table and suspend the pipe therein, said slips being suspended from said ring, said slips including a pair of slips having unconnected longitudinal edges, pivot means connecting their other longitudinal edges, handle means on each of said slips extending outwardly and rotatable in said ring, a trackway in said ring engageable by said handle means and taper-

11

ing downwardly and outwardly at decreasing rates of taper toward the periphery of the ring whereby the slips are lifted and retracted by pivotal movement of the pair of slips about their pivot means to separate said unconnected longitudinal edges as said ring is moved upwardly.

9. A slip operating mechanism including a lift ring adapted for placement over a rotary drilling table, said ring having an opening and a gate for passage of the ring to and from a pipe, a set of slips to fit the rotary table and suspend the pipe therein, said slips being suspended from said ring, said slips including a pair of slips having unconnected longitudinal edges, pivot means connecting their other longitudinal edges, handle means on each of said slips extending outwardly and rotatable in said ring, a trackway in said ring engageable by said handle means and tapering downwardly and outwardly at successive, decreasing inclinations to the horizontal so that the slips are moved upwardly and outwardly as the ring is lifted.

10. A slip operating mechanism including a lift ring adapted for placement over a rotary drilling table, said ring having an opening and a gate for passage of the ring to and from a pipe, a set of slips to fit the rotary table and suspend the pipe therein, said slips being suspended from said ring, said slips including a pair of slips having unconnected longitudinal edges, pivot means connecting their other longitudinal edges, handle means on each of said slips extending outwardly and rotatable in said ring, a trackway in said ring engageable by said handle means and extending arcuately downwardly and outwardly so that the slips are moved upwardly and outwardly and retracted by pivotal movement of the pair of slips about their pivot means

12

to separate said unconnected longitudinal edges as the ring is lifted.

- 5 11. A power assembly for operating pipe slips over a rotary table comprising, a ring disposed over but independent of the table and having an opening and a gate for passage of the ring to and from a pipe, an arm pivotally supported radially of the table, a pivoted connection between said ring and said arm, and means to 10 raise said arm to raise said ring and slips to clear said ring and slips of the rotary table opening, a set of slips suspended from said ring, supporting means extending outwardly from said slips and confined in said ring for circumferential 15 and radial movement relative thereto, said ring forming a circular trackway for rotation of said supporting means on and relative to said trackway when said slips are engaging a pipe therebetween.

WALTER E. LILJESTRAND.
